UNITED STATES PATENT OFFICE.

WILLIAM H. BLISS AND JEREMIAH W. BLISS, OF HAMILTON, MISSOURI.

WIRE-STRETCHER.

SPECIFICATION forming part of Letters Patent No. 293,406, dated February 12, 1884.

Application filed July 31, 1883. (Model.)

To all whom it may concern:

Be it known that we, WILLIAM H. BLISS and JEREMIAH W. BLISS, of Hamilton, Caldwell county, Missouri, have invented a new and Improved Wire-Stretcher, of which the following is a full, clear, and exact description.

Our invention consists of a reel-support, brake, and guides contrived for attachment to a wagon-box to be driven alongside of the line 10 of fence-posts for delivering wires to be attached to the posts and for stretching them along the posts, the attachment being arranged for readily taking out and putting in the reels when required, and also being contrived for 15 readily winding the wires onto the reels while in its place when it may be preferred to do so, all as hereinafter fully described.

Reference is to be had to the accompanying drawings, forming part of this specification, in 20 which similar letters of reference indicate corresponding parts in all the figures.

Figure 1 is a plan view of our improved wire-stretcher. Fig. 2 is a side elevation. Fig. 3 is a transverse section of the reel on line 25 xx of Fig. 2. Fig. 4 is a transverse section of one of the guide-eyes for the wires, and Fig. 5 is a longitudinal section of the said guide-eye.

We make a bed-frame, a , with lugs or ears b , and a binding-screw, c , to be fastened on a 30 wagon-box, d , crosswise, and having a sliding extension, e , to draw out of one end, on which frame we mount the wire-reel shaft f in bearings g of uprights h , having hinged caps i , that are fastened with hooks j , to be opened and 35 closed readily to take out and put in the shaft when desired. The shaft f has a crank, k , for turning it, a ratchet-disk, l , and a pawl, m , for holding it, and also a brake-lever, o , for regulating the unwinding of the wire from it. 40 Said shaft also has a disk, p , with stud-pins q and a nut, s , for securing the spools t , whereon the wires are wound. Below the shaft there is an elbow-lever, u , that is pivoted at v , and carries a guide-spool, w , in front of the reel, 45 which is used mainly in reeling wire onto the spool, but will sometimes be serviceable in reeling it off. On the extension-frame e there is a guide-stand, x , on the top of which there is a guide-pulley, y , with which there is a 50 guide-eye, a' , through which the wire b' passes from reel t onto said pulley y , and another

guide-eye, c' , through which the wire runs after passing around pulley y . From this latter guide the wire is attached to the post d' , from which it is to be stretched.

It will be seen that by applying the requisite friction to the reel-shaft f by the lever o any desired tension may be applied to the wire as the machine is moved along by the wagon to deliver the wire to the posts.

The guides a' and c' are made in parts that are jointed together at e' , and they have spring-fasteners f' to hold them together, the object being to apply or remove the wires without running them through the eyes to the end of the wire when it may be required to do so. Said eyes are funnel-shaped at the ends, to facilitate the running of barbed wire through them, and they are swiveled at g' to these supporting-arms h' , to allow them to turn as the wire may incline. These supporting-arms are pivoted to the stand x at the center of pulley y to swing around it for setting said eyes in different positions, and they rest on the slotted circular table i' , whereon they are fastened in any position by the clamp nuts and bolts j' , which swing along the slots l' in said table. For reeling off the wire onto the posts d' these guides will be set in about the positions represented in Fig. 1, the wire b' passing around 75 pulley y to the right hand; but for reeling on the wire the guides a' c' will be shifted to the other ends of their respective slots, and the wire, passing first through guide c' , will then pass around pulley y to the left hand, thence 80 through guide a' to the reel.

It will be seen that with this improved machine wires may be stretched along the fence-posts with great facility, and in case any ravine or other place may be encountered that 90 cannot be crossed by the wagon, the reel and wire may be readily taken out and carried along by hand until ground is reached where the wagon may be again used, when the reel and wire may be readily restored to the machine. The extension part e of the bed-frame is to be secured at any desired point by pins or screws m' , fitted in the frame a , to drop or screw into the holes n' of the said extension.

We propose to construct the frame a and 100 extension-frame e so that, having passed along the whole length of the fence in one direction,

the frame *e* can be shifted to the other end of frame *a*, and the machine can be used in the same manner on the same side of the fence and going in the reverse direction, the wire being drawn from under the spool in one direction and over it in the other direction.

Having thus described our invention, we claim as new and desire to secure by Letters Patent—

- 10 1. The combination, in a wire-stretching apparatus, of the reel-shaft *f*, guide-eyes *a* and *c*, and the guide-pulley *y*, the said reel-shaft being provided with a friction-lever, *o*, and a ratchet and pawl, *lm*, substantially as described.
- 15 2. The combination, in a wire-stretching apparatus, of the reel-shaft *f*, guide-eyes *a* and *c*, and the guide-pulley *y*, the said reel-shaft having hinged and hooked bearing-caps, and the guide-eyes being arranged to open and close for the removal of the reel and wire and the replacing of the same, substantially as described.
- 20 3. The combination, in a wire-stretching apparatus, of the guide-pulley *y* and the guide-eyes *a'* and *c'*, said guide-eyes being swiveled to their bearing-arms *h'*, and said arms pivoted

in the axis of the guide-pulley *y*, for shifting around the same, substantially as described.

4. The combination, in a wire-stretching attachment, of the guide-pulley *y* and guide-eyes *a'* *c'*, stand *x*, circularly-slotted table *i'*, and the supporting-arms *h'* of the guide-eyes, said arms being pivoted to the stand, and resting on and connected to the table, substantially as described.

35 5. In a wire-stretching attachment to be secured to a wagon-box, the combination of the bed-frame *a*, having ears or lugs *b*, and a binding-screw, the wire-reel mounted on said bed-frame, the extension *e* of said bed-frame, and the guide-eyes *a'* and *c'*, mounted on said extension, substantially as described.

40 6. The combination of the spool-guide *w*, mounted on the elbow-lever *u*, with the wire-reel *t*, and the guide-eyes *a'* and *c'*, and the guide-pulley *y*, substantially as described.
